CHECK CONTROLLING MEANS FOR VENDING MACHINES

Fairfield W. Hoban, New York, N. Y., assignor to
 Stewart and McGuire, Incorporated, New York,
 N. Y., a corporation of New York

Application May 25, 1936, Serial No. 81,593

22 Claims. (Cl. 194—97)

My invention relates to improvements in means for controlling the delivery of coins or checks to check controlled apparatus, and the same has for its object to provide a simple, reliable and efficient device which serves to arrest various counterfeit or spurious coins or slugs inserted and to return the same to the operator and to prevent delivery to such apparatus of defective coins or other checks liable to jam or clog the apparatus and interfere with the free operation thereof.

Further, said invention has for its object to provide a device of the character specified in which means are included for subjecting the checks, slugs or like devices to various tests and for preventing passage of checks or the like to the check controlled apparatus upon failure of such check to meet the test or tests imposed thereon.

Further, said invention has for its object to provide a device of the character specified in which mechanically actuated means are included for releasing the defective slugs or checks lodged within said device as a result of the failure of such checks to satisfy the tests imposed thereon.

Further, said invention has for its object to provide a device of the character specified in which means are included for subjecting the checks or coins inserted therein to dimensional and weighing tests.

Further, said invention has for its object to provide a device of the character specified in which magnetic means are included for arresting slugs of magnetic metal disposed therein while allowing such magnetic slugs or checks to be readily released and discharged from the device upon actuation thereof.

Further, said invention has for its object to provide a device of the character specified in which balanced weighers are included for retaining slugs or checks deficient in weight in the device until the same is actuated for releasing and discharging such deficient slug or check.

Further, said invention has for its object to provide a device of the character specified in which the coin passage thereof and its balanced weighers are co-ordinated to prevent delivery of the check to said weigher under appreciable momentum.

Further, said invention has for its object to provide a device of the character specified which is constructed to prevent the forcing of defective slugs lodging therein through the device into the control mechanism by means of a tool or other instrument.

Further, said invention has for its object to provide a device of the character specified which

is particularly adapted for controlling the delivery of coins to check controlled apparatus rendered operative by the action of coins of different denominations.

Further, said invention has for its object to provide a device of the character specified in which certain of the passages thereof are controlled to prevent delivery of a coin therethrough to the check controlled apparatus before the operation thereof allowed by a previously inserted coin is completed.

Other objects will in part be obvious, and in part be pointed out hereinafter.

To the attainment of the aforesaid objects and ends, my invention consists in the novel features of construction, and in the combination, connection and arrangement of parts hereinafter more fully described and then pointed out in the claims.

In the accompanying drawings;

Figure 1 is a sectional view on the line 1—1 of Fig. 2 of one form of device constructed according to and embodying my said invention;

Fig. 2 is a side elevation thereof with parts in section;

Fig. 3 is a front elevation thereof looking at the same in the direction of the arrows on the line 3—3 of Fig. 2;

Fig. 4 is a section view thereof on the line 4—4 of Fig. 2 looking in the direction of the arrows, parts being broken away to illustrate one of the operations of the device;

Fig. 5 is a horizontal section thereof taken on the line 5—5 of Fig. 1;

Fig. 6 is a view of the inner face of the back member of the device looking at the same in the direction of the arrows on the line 6—6 of Fig. 5, said plate being shown swung up into inverted position;

Fig. 7 is a similar view of the inner face of the fixed, front plate of the device, looking at the same in the direction of the arrows on the line 7—7 of Fig. 5;

Fig. 8 is a detail sectional view taken on the line 8—8 of Fig. 1 looking in the direction of the arrows.

Referring to the drawings, the coin controlled mechanism 10 is shown applied to a vending or dispensing means for dispensing or delivering merchandise, such as candy, nuts or similar articles in loose form and in measured quantities in accordance with the value of the coin inserted.

The apparatus controlled by the mechanism 10 comprises rotatable means 11 including a carrier or drum 12 mounted for rotation about a hori-

zontal axis below the open discharge end of a hopper 13 for receiving the commodities, the drum 12 being provided with pockets 14 adapted to successively register with the hopper for receiving the commodity therefrom. The drum 12 is preferably secured for rotation upon suitable shafting 15 having a bearing 16 at the front in a support or bridge 17, the rear end of the shafting 15 being journaled in a suitable support, such as the rear wall of the casing employed to enclose the mechanism or apparatus. The shafting 15 has an actuating member or knob 18 at the front end thereof adapted to be rotated in a clockwise direction.

15 To facilitate the assembly of the apparatus within the casing, and its removal therefrom, the shafting 15 preferably consists of aligned sections 19 and 20 while the drum 12 carried thereby preferably consists of two telescoping sections 21 and 22 in adjustable sliding engagement with each other to allow adjustment of the size of the pockets. The forward shaft section 19 carries the coin controlled mechanism 10 and is rotatably supported in the bridging member 17 and retained against axial movement therein by said mechanism 10 and the knob 18. The rear end of the shaft section 19 receives the forward section 21 of the drum 12 which is provided for this purpose with an axial sleeve 23. The shaft portion 19 and drum section 21 are keyed to each other against relative rotation by suitable means such as the flats 24.

30 By the construction above described, the shaft section 19 together with the mechanism and parts disposed thereon may be readily disengaged from the drum section 21 and withdrawn from the casing of the vending machine.

35 The rear drum section 22 interfits the front drum 21 in complementary relation thereto and is provided with an axial collar 25 at the rear thereof adapted to receive the forward end of the shaft section 20 which enters the sleeve 23 of the forward drum section 21. The drum section 22 is capable of being slid along the shaft section 20 to vary the length of the pockets 14, and is secured in any adjusted position by means of the set screws 26.

40 The intermediate portion of the operating means or shafting 15 is also preferably supported by a member or hanger 27 attached to the hopper 13 and depending therefrom, said member 27 having an annular end portion 28 receiving the collar 29 formed on the forward end of the drum 14.

45 The coin controlled mechanism 10 preferably comprises an intermediate integrally formed member 30 including a ratchet element 31 having a succession of steps 32 thereon corresponding in number with the maximum number of coin units for which the apparatus is adapted. The member 30 also includes an axial sleeve 33 having oppositely projecting hub portions 34 and 35 adapted to receive the shaft 19 upon which the member is mounted.

50 The coin controlled mechanism also includes means 36 for properly centering the same in the successive locking positions. Such means preferably includes a centering portion 37 formed upon the front face of the ratchet element 30 including a succession of recesses 38 corresponding in number with the number of steps 32 on the ratchet 31 and arranged in corresponding relation to said steps. The centering element 37

55 frame member 17 and provided with a coil spring 41 for retaining the same in yielding engagement with the successive recesses 38. The recesses 38 and the nose 42 of the dog 39 are preferably of complementary arcuate contour, the interengaging arcuate portions having a camming relation to insure the proper positioning of the parts in centered positions as the mechanism is rotated clockwise through the successive steps or positions thereof and to insure return to centered position upon a partial or incomplete movement in a clockwise direction as hereinafter more fully described.

60 The forward hub 34 is adapted for the mounting of a forward member or element 43 of the control mechanism 10. Such element 43 is provided with an axial opening 44 therein for receiving the hub 34 and includes a disk portion 45 having coin receiving pockets 46 formed upon the rear face thereof. The pockets 46 are of arcuate formation adapted to receive and hold therein coins of various denominations, such as a one cent piece or a five cent piece (a nickel). The pockets 46 correspond in number with the number of successive locking positions of the mechanism and are disposed in predetermined relation to the successive centering positions to allow the coins to drop vertically into the same by gravity and to discharge any coin therein upon movement of the actuator a complete step in a clockwise direction.

65 The forward face of the member 43 has formed thereon a ratchet portion or element 47 co-operating with a detent 48 for preventing rotation of the mechanism in a counter-clockwise direction. The detent 48 is preferably pivotally mounted at 49 to the frame member 17 co-axially with the pivot 40 of the dog 39, and is retained in engaging relation with the ratchet 47 by the spring 50. The ratchet 47 is provided with more steps or teeth 51 than the ratchet 31 has, the teeth relationship being three to one in the embodiment of the invention illustrated, to allow rotation of the actuator in a clockwise direction 45 a part of a complete step without the detent 48 dropping into the next succeeding dwell of the ratchet 47, for a purpose hereinafter described.

70 The member 43 is preferably keyed to or interlocked with the intermediate member 30 by forming lugs 52 upon the hub 34 adapted to be received into corresponding slots or recesses 53 formed in the member 43.

75 Another member or disk 54, provided with an axial opening 55 for receiving the hub 35, is 55 rotatably mounted upon said hub against the rear face of the intermediate member 30. The member 54 is of relatively greater diameter than that of the ratchet 31 and is provided with a notch or clearance 56 in the periphery 57 thereof for receiving the offset nose 58 of a coin actuated member or detent 59 co-operating with the ratchet 31.

80 The detent 59 is pivoted at 60 to the frame member 17 at the side thereof opposite the dog 39 and detent 48 in position to engage the ratchet 31 and to lie in operative relation to the coins moved into camming relation thereto when the operating means is rotated with a coin in any pocket thereof. The detent 59 is retained in engagement with the ratchet 31 by the spring 61, and is provided with an intermediate step or abutment 62 on the lower edge thereof adapted to engage and ride upon the dwells 63 of the ratchet 31 intermediate the teeth 32. In the nor- 75

5 mal position of the mechanism the abutment 62
engages an intermediate portion of a dwell 63
to allow a limited or slight rotation of the mecha-
nism in a clockwise direction and return before
the abutment 62 engages the next succeeding
step of the ratchet 31. The detent 59 has a
laterally projecting pin 64 extending transversely
over the coin receiving means 46 in position to be
10 actuated by the coins therein as hereinafter
described.

15 The disk member 54 is retained in position
upon the hub 35 by means of the sleeve or retaining
member 65 secured to the hub 35 and shaft
19 by the transverse pin 66 which also serves to
secure the member 30 against rotation relative
to the shaft 19.

20 The disk member 54 serves as means for sup-
porting the detent 59 disengaged from the ratchet
31 to allow a complete revolution of the operat-
ing means when the detent is actuated by a coin
of greater diameter, such as the nickel, the
periphery 57 of said disk 54 serving as a dwell
upon which the nose 58 of the detent rides dur-
ing said revolution. Said detent disengages said
25 dwell 57 and drops into the clearance space 56 at
the completion of the revolution to again engage
the ratchet 31 and lock the mechanism.

30 For this purpose, the disk 54 has a yieldable
slip connection 67 with the member 30 to allow
the member 54 to rotate with the operating
means when the detent 59 is actuated to clear
said member, and to allow relative movement of
the operating means when said detent is actu-
35 ated by a coin of lesser diameter, such as a cent
piece, to clear the ratchet 31 but not the disk 54.

40 The slip connection 67 is such as to lock the
disk 54 to the member 31 in a succession of rela-
tive positions corresponding in number with the
ratchet steps 32. As shown, the ratchet member
31 upon the back face thereof is provided with a
45 series of recesses 68 disposed in corresponding
relation to the steps 32 while the disk 54 has an
opening 69 therein adapted to register with the
recesses 68 in the successive positions. The open-
ing 69 receives a locking element 70 retained in
50 place by a leaf spring 71 and adapted to enter
the successive recesses 68 to lock the parts to-
gether for joint rotation.

55 As shown the clearance space 56 is sized to
allow in each of the locking positions of the disk
54 limited movement of the operating means in
a clockwise direction and return without the nose
58 of the detent 59 engaging the abutment 72 at
the end of the clearance space. The successive
60 locking positions of the slip connection 67 are lo-
cated to lock the disk 54 to ratchet 31 with said
abutment 72 in the same position relative to the
successive locking steps or positions. When the
65 detent 59 is elevated by a coin of smaller dia-
meter upon rotation of the operating means, the
nose 58 of the detent engages the abutment 72
to disengage the slip connection 67 and retain
the disk 54 against movement with the operating
70 means, the parts relatively moving to interlock
in the next succeeding relative position thereof
ready for operation upon insertion of another
coin.

75 The coins for controlling the release of the
mechanism 10 are controlled in their passage to
the mechanism by a fraud preventing device and
scavenger 13 particularly adapted for coins of
two different denominations to be delivered to the
mechanism 10.

75 The device 13 includes a front member or plate

74 having a depending portion 75 and secured
through said depending portion 75 to the bridg-
ing member 17 by means of a screw 76 in posi-
tion above the coin pockets 46. A co-operating
member or plate 77 disposed at the rear of the
plate 74 is pivoted at its upper edge to the upper
edge of the plate 74 for swinging movement out-
wardly relative to the fixed plate, said members
being provided for this purpose with the ears
78 receiving the pivot pin 79 and being normally
10 retained in closed relation by means of a coil
spring 80 upon said pivot pin 79 with its ends
engaging the plates in the usual manner.

15 The two members 74 and 77 when in closed re-
lation form the coin guiding passages 81 and 82
15 at opposite sides of the medial line thereof di-
mensioned to correspond with the diameter and
thickness of the cent and of the nickel respec-
tively. The two coin passages 81 and 82 are
20 separated from each other by a vertical rib or
spacer 83 preferably formed upon the plate 74 at
the medial line thereof. The cent passage 81
is defined by means of the upper and lower par-
allel rib or spacer portions 84 and 85, one of
25 said ribs being formed upon the inner face of the
member 74 and the other thereof upon the cor-
responding face of the member 77, and both ex-
tending towards the medial line of the device at a
downward inclination. The rib member 84 is
30 spaced from the contiguous end of its plate 74
to provide an opening 86 between the plates for
the insertion of the coin. The rib 85 extends
from the contiguous end of the member 77 be-
35 low the coin slot 86 and terminates at its inner
end short of the medial rib 83 to form the down-
ward passage extension 87 therebetween. The
nickel passage 82 is defined by similarly arranged
40 ribs 84* and 85* and includes the coin opening
or slot 88 and the downward passage extension
89. The nickel side of the plate 77 is preferably
45 made of reduced thickness, as indicated at 90,
Figs. 5 and 6, to compensate for the greater
thickness of the nickel. In practice, the coin in-
lets or slots 86 and 88 are adapted to register
or align with corresponding slots in the usual
50 casing which receives the mechanism.

55 The plate 74 below the medial rib 83 substan-
tially at the juncture of the depending portion 75
with the body of the plate has a part 90 thereon
forming anvil portions 91 and 92 disposed respec-
tively at the bases of the passage extensions 83
and 88 in the paths of the respective coins, and
extending downwardly and outwardly to points
contiguous to the corners 93 and 94 of the lower
edges 86 and 88 of the plate 74 in position to de-
55 liver the coins to the coin weighers 98 and 99.

60 The weighers 98 and 99 are pivoted at 100 in-
termediate their ends to the lower ends of the
arms 101 depending from the movable plate 77.
Each weigher 98 and 99 has an adjustable weight
102 threaded upon the outer end thereof and se-
cured in adjusted position by the set screw 103 to
slightly overbalance the inner ends 104 of the
65 weighers 98 and 99 and cause the same to nor-
mally engage the lower edges of the plates 74
and 77 in position to receive the coins rolling from
the ledges 91 and 92. The upper sides of the
70 coin carrying portions 104 of the weighers are
preferably curved longitudinally to correspond
with the curvatures of the periphery of the coin
75 to be received thereby and are provided with
longitudinally extending tracks or grooves 105
(Fig. 8) in which the coin rides. The cent
weigher 98 is adjusted to swing downwardly to
the lowermost position shown in broken lines 75

(Fig. 7) when a cent of standard weight is deposited thereon while the nickel weigher 99 is adjusted to swing downwardly to a similar position when a nickel of standard weight is deposited thereon. Discharge of coins from between the plates at the ends thereof is prevented by forming the vertical ribs 106 and 107 upon the plate 77 below the ribs 85 and 85^a which close the coin passages at these points.

10 The weighers when depressed deliver the coins thereon to the common outlet passage 108 formed between the inner side of the depending portion 75 and a platelike extension 109 of the slug collecting tray 110. For the purpose the part 75 is formed with the spacer portions 111 to which the tray extension 109 is secured. The passage 108 as thus formed has an inlet 112 through which the cent passes and inlet 113 at the opposite side through which the nickel passes and the 20 common discharge outlet 114 located vertically above the coin pockets 45 for discharge therein.

Slugs of magnetic material, otherwise conforming to the dimensional or weighing tests imposed upon the inserted check or slug, are held within 25 the device by the permanent magnets 115 and 116 located to have their fields concentrated in the lower portion of the coin passages immediately above the weighers 98 and 99 in position to attract the magnetic slugs as the momenta thereof are absorbed by the anvil ledges 91 and 92, thereby taking the weight of the magnetic slugs from the weighers 98 and 99. The fields of the magnets 115 and 116 are adjusted in strength to allow the slugs held thereby to be released and 35 discharged when the movable plate 77 is actuated.

In the present invention the coins or checks inserted at 86 and 88 travel inwardly and downwardly towards the medial rib 83, and then drop downwardly upon the ledges 91 and 92 which absorb the momentum of the devices or reduce their 40 velocity and impose a change of direction of travel thereon to enable the checks to roll onto the weighers 98 and 99 without appreciable momentum so that the weighers reflect more exactly the 45 true weight of the various slugs or checks which pass thereto.

In case a slug or check inserted in the apparatus to operate the vending machine lodges in the scavenger 73 no proper coin will be seated in 50 a coin pocket 46 for releasing the detent 59, and hence the machine cannot be operated to dispense the commodity.

In the present invention however the control mechanism 10 is designed as above described to 55 allow a limited movement of the operating means 11 in a clockwise direction from each centered position and the return thereof to said position for actuating the scavenger 73. For this purpose the movable plate 77 of the scavenger is connected by 60 a link 117 with the centering dog 39. The dog 39 is provided with a rearwardly extending arm 118 clearing the slug returning chute or tray 110 located below the scavenger for receiving the coins, slugs and devices released therefrom for return 65 to the operator. The movable plate 77 is also provided with a normally extending arm 119, the link 117 being loosely connected at the ends thereof to said arms 118 and 119.

When a defective or improper coin or similar 70 device is inserted into the scavenger and remains therein, upon rotation of the knob 18 the dog 39 is cammed upwardly as shown in Fig. 4 to swing the plate 77 together with the weighers 98 and 99 outwardly to release any device lodged between 75 the plates 74 and 77 or resting upon said weighers.

The movement of control 10 allowed for operating the scavenger is from the position shown in Fig. 1 to the position where the detent abutment 62 engages the contiguous step 32 of the ratchet 31 to prevent further rotation. When the knob 18 is released the spring controlled dog 39 by a camming action returns the mechanism to the centered position, and the spring 80 acts to close the scavenger.

In the discharging or releasing operation of the 10 scavenger 73, slugs or other checks which lodge in the scavenger immediately below the slot openings 86 and 88 upon the ledges 85 and 85^a are deflected rearwardly as the same fall forwardly from the said ledges by the rearwardly directed 15 deflecting portions 120 formed on the lower outer edges of the fixed plate 74. The portion 90^a forming the anvil edge 92 for the nickel is likewise provided with a beveled deflecting surface 121 for insuring proper deflection of a good nickel 20 into the return chute 110 in certain cases as hereinafter more fully described.

The fixed plate 74 is also provided with rib portions 122 extending from the deflectors 120 upwardly and inwardly below the rib portions 85 25 and 85^a carried by the movable plate 77 and terminating at the inner ends of said rib portions 85 and 85^a, the ends 123 of said lower ribs 122 being beveled or chamfered to form flush extensions of said rib portions 85 and 85^a. The ribs 122 30 together with the deflectors 120 are located to prevent defective coins or slugs lodging in the apparatus from being pushed or prodded for discharge into the control mechanism by means of a tool or other instrument inserted surreptitiously 35 through the slot openings 86 or 88 and manipulated therein, and prevent the insertion of such a tool or instrument into the apparatus for actuating the weighers when a slug too light to swing the same is located thereon. The function of the 40 parts 120 and 122 is such that the tool when it engages the same forces the plates apart sufficiently to deflect the tool away from the operating parts and cause the discharge of any slug 45 lodged in the scavenger.

The apparatus embodying the present invention also includes means 124 for insuring delivery of full value in commodity upon the insertion of each nickel into the apparatus.

In the coin controlled mechanism herein disclosed when a nickel is inserted the detent 59 is elevated to clear the member 54 and to ride upon the periphery 57 thereof and to be released or disengaged from the ratchet 31 for a complete revolution of the operating means before again engaging the ratchet 31 to lock the mechanism. If an operator should insert a nickel and only rotate the knob 18 through a part of a revolution, say to deliver the commodity from two or three of the five pockets 14 of the rotor 12, the detent 60 59 remains upon the member 57 disengaged and will so remain until the revolution is completed. If a second nickel, in the absence of the protective means 124, should now be inserted in the apparatus, it would pass through the scavenger and 65 into one of the pockets 46 to be retained in the apparatus. Since the operating means can only be rotated through the remaining unfinished part of the revolution before again locking, the second operator will not then receive full value for the 70 nickel inserted, but only the quantity remaining due from the last operation.

The means 124 to this end includes an arm 125 pivoted at one end 126 to the front face of the scavenger member 74 at one side thereof and 75

above the detent 59. The opposite end of the arm 125 is directed inwardly to form a finger 127 riding in the arcuate slot 128 registering with the vertical passage extension 89 of the nickel coin chute or passage, and terminating at its lower end in a recess 129 formed in the anvil portion 92. The opposing portion of the movable plate 71 is preferably offset, at 130 to provide clearance for the end of the finger 127 which spans the coin passage. The arm 125 is connected to the detent 59 by means of a link 131 pivoted at one end 132 to an intermediate portion of the detent and having a relatively loose pivotal connection 133 with an intermediate portion of the arm 125 at its opposite end.

The finger 127 in the lowermost position thereof registers with the recess 129 to allow a nickel to be deflected by the anvil 92 onto the weigher 99 for delivery to the control mechanism 10. The resulting actuation of the detent 59 actuates the arm 125 to position the finger 127 at the upper end of the slot 128 in the path of any second nickel inserted as shown in broken lines at A (Fig. 4) and prevent its passage to the control mechanism. The second operator must therefore complete the revolution of the operating means through the remaining dispensing steps and therefore obtain for his own use the commodity due from the previous operation. When the second nickel is inserted and retained in the scavenger as at A by the finger 127, the rotation of the operating means through the next succeeding step to complete the previous revolution actuates the centering dog 42 to open the scavenger 35 and cause return of the second nickel, said nickel in dropping glancing off of the beveled edge 121 to insure delivery thereof into the return chute 110.

The operation of the scavenger or coin controlling means 73 will be largely obvious from the foregoing description.

When a cent is inserted at 86, the check if of the required diameter and thickness rolls down the passage or chute 81 and into the vertical extension 83 thereof into impact with the anvil 91 which reduces its velocity. The check then rolls in the reverse direction onto the weigher 98 which then swings downwardly to the position shown in broken lines (Fig. 7), if the check is of the required minimum weight, to deliver the check or cent to the control mechanism. A similar measurement, control and weighing of the nickel is effected in the coin passage or chute 82 and the extension 89 thereof to deliver said nickel in like manner to the control mechanism. The magnets 115 and 116 serve to attract and hold any magnetic slugs inserted immediately above the anvil portions and weighers in position to be readily released upon actuation of the scavenger. Defective or other checks or slugs lodging or being retained in the scavenger passages or upon the weighers 98 and 99 are released therefrom upon limited rotation of the operating means in the manner above described.

When a cent piece drops into one of the coin pockets 46, it is moved by the operating means into engagement with the pin 64 to lift the detent 59 out of engagement with the ratchet 31, the coin clearing said pin in time to allow the detent to drop back and lock the mechanism in the next succeeding position. During this operation the nose 58 of the detent 59 engages the abutment 12 of the disk member 54 to retain the same against movement with the operating means, the slip connection 67 releasing to allow

such relative movement. During this movement the drum 12 rotates one step to discharge a measured quantity of the commodity into the usual chute for delivery to the purchaser. The ratchet 31 and disk 54 then interlock in the next 5 succeeding relative position.

When a nickel drops into one of the pockets 51, upon rotation of the actuator 18, the larger coin elevates the detent 59 to a greater extent to clear the disk 54 and to drop upon the dwell 57 thereof as the coin clears the pin 64. Hence, the detent 59 remains disengaged from the ratchet 31 to allow a complete revolution of the rotor 12 and disk 54, the detent dropping into the clearance 56 of the disk 54 to engage the ratchet 31 15 at the end of the revolution for locking the mechanism. During said revolution all of the drum pockets 14 are brought successively into discharging position for delivering five measured quantities of the commodity to the purchaser, and 20 the member 124 prevents the insertion of a second nickel before the revolution is completed.

The apparatus or mechanism 10 which constitutes the subject matter of my co-pending application filed December 28, 1935, Serial No. 25 56,558, is responsive to coins of different values to release said mechanism for rotation of the operating means in one direction through a single 30 step or a succession of steps for delivering one or more measured quantities of the commodity 30 or goods corresponding to the value of the coin inserted, the apparatus resetting or resuming normal position after each complete operation, without regard to the value of the coin inserted, 35 ready for operation by the next coin, and requiring only a single revolution of the actuator 18 to deliver the maximum quantity of commodity.

The scavenger or fraud preventing device 73 constituting the subject matter of the present 40 application insures against malicious, surreptitious or other operation of the vending apparatus by means of slugs, defective coins or other devices which might clog, jam or otherwise damage said mechanism or obtain the delivery of 45 goods without value received. Said scavenger is also particularly adapted for control by said control mechanism 10 to release any checks or slugs lodged therein and to prevent acceptance of a second nickel before a previous nickel operation 50 is completed.

Having thus described my invention, what I claim and desire to secure by Letters Patent is:

1. The combination of a check controlled mechanism including a locking member actuated by 55 a coin of one denomination for allowing a step movement of said mechanism, and means for retaining said locking member when actuated by a coin of second denomination disengaged for movement of said mechanism through a succession of steps, with means including separate passages for the passage of the coins to said locking member, and means actuated by said locking member for obstructing the passage of the coin of second denomination until the movement 60 through a succession of steps is completed.

2. The combination of a check controlled mechanism including locking means actuated by a coin of one denomination for allowing a step movement of the mechanism and means for retaining said locking means when actuated by a coin of a second denomination disengaged for movement of said mechanism through a succession of steps, with coin delivering means including relatively movable members forming coin 75

passages therebetween, means actuated by said locking means for obstructing the passage for the coin of second denomination during movement of said mechanism through a succession of steps, and means for actuating said coin delivering means by operation of said mechanism.

3. The combination of a check controlled mechanism including ratchet means for allowing step rotations of said mechanism, means for retaining said ratchet means disengaged for rotation of said mechanism through a succession of steps, and means for centering said mechanism in the successive positions, with means including passages for delivering coins of different denominations to said ratchet means, means for obstructing one of said coin passages when said ratchet means is retained disengaged by said second named means, and means controlled by said centering means for actuating said coin delivering means for the return of devices lodged therein.

4. The combination of a check controlled mechanism including ratchet means for allowing a step movement of said mechanism, and means for retaining said ratchet means disengaged for a complete revolution of said mechanism, with coin delivering means including members pivoted together for opening movement and forming coin passages therebetween, an arm pivoted to one of said members and extending into one of said passages normally in position to clear the same, means for actuating said arm from said ratchet means for obstructing the passage controlled thereby, and means for opening said pivoted members by the operation of said mechanism.

5. The combination of a check controlled mechanism including a pivoted locking member, and means for retaining said locking member disengaged for a complete revolution of said mechanism, with a pair of members pivoted together for opening movement and forming a coin passage therebetween, an arm pivoted to the outside of one of said last named members and extending into said passage normally in position to clear the same, a connection between said locking member and said arm for obstructing said passage when said locking member is retained disengaged by said first named means, and means for actuating said pivoted members by the operation of said mechanism.

6. A device of the character described comprising a pair of members pivoted together at the upper edges thereof and forming a coin passage therebetween, the fixed one of said members having a portion forming an anvil at the base of said passage, and a slot therein formed in part in said anvil, a pivoted member associated with said first mentioned members for receiving the coin from said anvil, an arm pivoted to said fixed member and having a finger extending into said slot normally below the plane of said anvil, and means for actuating said arm for moving said finger into coin obstructing position in said passage.

65 7. A device of the character described comprising relatively movable members forming a check measuring passage therebetween, an anvil portion at the base of said passage, a pivoted weigher at the lower edges of said members forming a closure for the base of said passage beyond said anvil portion, said weigher serving to retain an underweight check received from said anvil portion in position between said members, and means below said anvil portion having a discharge passage therein and depending from one

of said members at the end of said weigher for receiving the check upon the depression of the weigher thereby.

8. A device of the character described comprising relatively movable members forming a check measuring passage therebetween, an anvil portion at the lower end of said passage, a pivoted weigher disposed to receive the check from said anvil, and a magnet having the field thereof concentrated at the lower portion of said passage above said weigher.

9. A device of the character described comprising a fixed member, a member pivoted thereto for swinging movement, said members having portions upon the inner faces thereof forming a coin passage and a coin inlet at the top thereof, said portions including a coin supporting rib upon said pivoted member disposed below said coin inlet, and said fixed member having a portion extending angularly from the lower edge thereof and underlying said coin supporting rib below said coin inlet.

10. A device of the character described comprising a pair of members pivoted together at the upper edges thereof for opening movement of one member relative to the other, said members having ribs upon the inner faces thereof providing a coin passage therebetween and a coin inlet at the top thereof, one of said members having the rib thereon extending downwardly and inwardly below said inlet opening, and the second of said members having a portion extending angularly from the lower edge thereof and underlying said last named rib below said coin inlet and a rib upon the inner face of the second member extending upwardly and inwardly from said angularly extending portion and underlying the inner portion of the rib on said first member.

11. A device of the character described comprising relatively movable plates having downwardly and inwardly extending ribs and a vertical extending medial rib forming separate coin passages, anvil portions formed at the base of said medial rib at opposite sides thereof, and pivoted weighers for receiving checks from said anvil portions.

12. A device of the character described comprising a fixed plate, a plate pivoted thereto, said plates having passages therebetween for measuring checks of different sizes, pivoted weighers upon the pivoted plate at the discharge ends of said passages, and a common outlet from said pivoted weighers.

13. A device of the character described comprising a fixed plate, having a projecting lower part including anvil portions, a plate pivoted to said fixed plate at the upper edges of said plates, said plates having check passages therebetween in communication with said anvil portions, pivoted weighers at the lower edges of said movable plate extending towards said anvil portions, and a closure member seated upon said projecting lower part and forming therewith a common outlet passage from the weighers.

14. A device of the character described comprising a fixed plate, a pivoted plate associated therewith, said plates having check passages therebetween, oppositely directed anvil portions formed at the lower center of said plates, and weighers pivotally mounted upon said movable plate and associated with anvil portions.

15. A device of the character described comprising a fixed plate, a plate hinged thereto at the contiguous upper edges of said plates, said plates having check controlling passages there-

- between at opposite sides of the vertical medial line thereof, protective means at the lower portions of certain of said plates, and pivoted weighers at the lower ends of said passages below said protective means.
- 5 16. A device of the character described comprising a pair of members pivoted together at the upper edges thereof for opening movement of one member relative to the other, said members 10 forming a coin passage therebetween and a coin inlet at the top thereof and including a longitudinally extending passage forming rib upon the inner face of one of said members below said coin inlet, and the other member having means there- 15 on underlying said rib and forming therewith a succession of barriers co-operating to prevent undue manipulation of the device by an object inserted between said members through said coin inlet.
- 20 17. A device of the character described comprising a pair of members pivoted together at the upper edges thereof for opening movement of one member relative to the other, said members forming a coin passage therebetween and a coin 25 inlet at the top thereof and including a longitudinally extending passage forming rib upon the inner face of one of said members below said coin inlet, coin weighing means movably mounted below said device in operative relation to the dis- 30 charge end of said passage, and means on said other member underlying said rib and forming therewith a succession of barriers co-operating to prevent access of an object inserted through said coin inlet to said weighing means.
- 35 18. A device of the character described comprising a pair of plates pivoted together at the upper edges thereof for opening movement of one plate relative to the other, said plates having passages therebetween for measuring checks 40 of different sizes, pivoted weighers upon one of said plates at the discharge ends of said passages, and a common outlet from said pivoted weighers.
19. A device of the character described comprising a fixed member, a member pivoted thereto 45 at the upper edges of said members, said members having ribs upon the inner faces thereof forming separate coin passages open at the bases of said members, weighing members pivotally mounted upon the pivoted member at the lower 50 edges of said members in positions to normally form closures for the open bases of said passages, and a portion depending from said fixed member between said weighing members and having a common outlet provided with openings at the sides thereof towards said weighing members for receiving coins therefrom upon depression of said weighing members by the coins.
20. A device of the character described comprising a pair of members pivoted together at the upper edges thereof for opening movement of one member relative to the other, said members forming a coin passage therebetween and a coin inlet at the top thereof and including a longitudinally extending passage forming rib upon the inner face of one of said members below said coin inlet, and the other member having a rib upon the inner face thereof including a portion underlying said first-named rib and a portion extending beyond the inner end of said first-named rib and forming a registering extension thereof. 15
21. A device of the character described comprising a pair of members pivoted together at the upper edges thereof for opening movement of one member relative to the other, said members forming a coin passage therebetween and a coin inlet at the top thereof and including an inwardly and downwardly extending passage forming rib upon the inner face of one of said members below said coin inlet, and the other member having an upwardly and inwardly extending rib upon the inner face thereof including a portion underlying said first-named rib and a portion forming a registering extension of said 30 first-named rib. 25
22. A device of the character described comprising a pair of members pivoted together at the upper edges thereof for opening movement of one member relative to the other, said members forming a coin passage therebetween, a coin inlet at the top thereof and a discharge outlet at the lower end of the passage in offset relation to said coin inlet, and including an inwardly and downwardly extending passage forming rib upon the inner face of one of said members below said coin inlet, the other member having an inwardly and upwardly extending rib upon the inner face thereof including a portion underlying said first-named rib and a portion forming a registering extension of said first-named rib, said ribs providing a succession of barriers co-operating to prevent manipulation of the device by an object inserted between said members through said coin inlet, and coin weighing means movably mounted on the device below said barriers in operative relation to said discharge outlet. 35 40 45 50
